C. S. BURTON.
VACUUM FUEL FEED DEVICE FOR INTERNAL COMBUSTION ENGINES.
APPLICATION FILED JUNE 16, 1920.

1,408,440.

Patented Mar. 7, 1922.

UNITED STATES PATENT OFFICE.

CHARLES S. BURTON, OF OAK PARK, ILLINOIS.

VACUUM FUEL-FEED DEVICE FOR INTERNAL-COMBUSTION ENGINES.

1,408,440.

Specification of Letters Patent.

Patented Mar. 7, 1922.

Application filed June 16, 1920. Serial No. 389,284.

To all whom it may concern:

Be it known that I, CHARLES S. BURTON, a citizen of the United States, residing at Oak Park, in the county of Cook and the 5 State of Illinois, have invented certain new and useful Improvements in Vacuum Fuel-Feed Devices for Internal-Combustion Engines, of which the following is a specification, reference being had to the accompanying 10 drawings, forming a part thereof.

The purpose of this invention is to provide an improved means for supplying fuel to the carbureter of an internal combustion engine, by means of a supply tank located 15 at a lower level than the carbureter. It consists in the elements and features of construction shown and described, as indicated in the claims.

In the drawings:—

20 Figure 1 is a diagrammatic view showing certain parts in the organization of an internal combustion engine, and in fuel supply means on a motor vehicle, said fuel supply means comprising this invention.

25 Figure 2 is a vertical axial section of a float chamber and connections therefrom embodying the main elements of this invention.

Figure 3 is a partly sectional view of the chamber shown in Figure 2, a portion of the 30 chamber being broken away and a section being made at the line, 3—3, on Figure 2.

Figure 4 is a view similar to the upper part of Figure 2, showing the movable parts in a different position from Figure 2.

35 Figure 5 is a sectional view similar to Figure 2, showing a modified construction.

The drawings show in a conventional way in Figure 1 the carbureter of an internal combustion engine, of which the float chamber is seen at 1, a main fuel supply tank at 40 a low level shown at 2; a conduit from the tank, 2, to the carbureter comprising pipe members, 3, 3, a T-fitting connecting them shown at 4, which contains check valves as 45 further hereinafter described opening for flow from the tank toward the carbureter; a float chamber, 6, having the distinguishing elements of this invention connected by a pipe member, 5, with the stem of the T-fitting, 3^a.

50 The pulsator, 9, consists of a cylinder and a piston, 9^a, therein, operated by any suitable means for reciprocating the piston, as an eccentric 10, on any rotating shaft of or driven by the engine, indicated by 11.

A pipe, 12, connecting the pulsator with the 55 float chamber, 6.

Before proceeding with detail description of the parts directly concerned in the invention, its general principle and mode of operation may be set forth. The pulsator produces alternate compression and suction which is communicated to the chamber, 6, the suction stroke tending to produce a partial vacuum in that chamber and thereby operating suctionwise to draw the liquid from 60 the low tank, 2, through the pipe, 3, and past a check valve, 8, shown in the left hand member of the T-fitting, 3^a, and up through the stem pipe, 5, into the chamber, 6. The compression impulse of the pulsator 65 producing pressure upon the top of the liquid lifted into the chamber, 6, tends to force it out through the pipe member, 5, and past the check valve, 7, and on through the pipe member, 3, to the carbureter. Thus the device operates as a pump for pumping the liquid from the tank to the carbureter. In the absence of any means to modify the action, this pumping would proceed indefinitely as long as the engine is in operation 70 for operating the pulsator; and thereby the carbureter is liable to be oversupplied, and the pumping still continuing the liquid would eventually be drawn up through the pipe, 12, and the chamber of the pulsator would 75 become filled with liquid, and thereupon thereafter, there being no relief or cushion for the pressure stroke, the connections would be overstrained and eventually ruptured.

In order to render the device practically operative, therefore, means must be provided for limiting the pumping action before the oversupply exceeds the capacity 80 of the chamber, 6. For this purpose provision is made for defeating the pumping ac- 85

tion of the pulsator so far as lifting the liquid from the low tank, 2, is concerned, by providing an atmosphere vent to satisfy the suction impulse of the pulsator, said vent being normally closed, but opening when 90

the chamber, 6, is filled to a predetermined point. This vent device is shown in two forms. In the form shown in Figure 2, the cap plate, 13, of the chamber, 6, has formed 95 upon its upper side a diametrically extending boss, 4, which is bored at 4^a from one end and tapped at that end, to receive the pipe, 100

105 communicating through a port, 13^a, in

the cap with the cavity of the chamber, 6. From the other end of the boss, 4, it is bored at 4°, to afford air entrance through the open end, of the bore which stops short of 5 meeting the bore, 4^a, so as to leave standing the partition wall or diaphragm, 4^a, through which there is made a central aperture, the opposite ends of which, 4^a and 4^b, constitute two ports through both of which the air 10 must pass for entrance to and emergence from the bore, 4^a, and the cavity of the chamber, 6, which are practically functionally one chamber. These two ports, 4^a and 4^b, are controlled by disk or wafer valves 14 15 and 15, which stand on edge and are substantially vertical in their seated position, and inclined slightly away from the seats at their open position, the valve, 14, being checked at said inclined open position by check pins 16, 20 of which there are shown three driven in through the wall of the boss, 4, a short distance from the partition or diaphragm, 4^a, to limit the movement of the valve, 14, away from its seat. The valve, 15, is similarly 25 stopped within a short distance of its seat by the inner end of a strainer device, 16^a, which is entered through the open end of the bore, 4^a, and centered by a collar, 4^b. In the chamber, 6, there is provided a float, 17, having a stem, 17^a, extending down through the pipe member, 5, and obtaining guidance for itself and the float in a spider, 18, mounted in the discharge opening from the chamber, 6, to which the pipe member, 5, is connected and 30 35 by a pin, 19, inserted transversely through the lower end of the stem of such length as to substantially span the pipe, 5, interiorly. Pivoted upon a downwardly-extending lug, 13^b, of the cap plate, 13, there is a bell 40 crank lever, 20, having an up-standing arm, 20^a, extending up through the slot, 13^a, in the cap plate, 13, and terminating in position for swinging toward and from the disk valve, 14. This valve, 14, has a slender 45 stem, 14^a, projecting through the ports, 4^a and 4^b, and of such length as to reach the valve, 15, when the valve, 14, is tilted toward its seat and before it reaches its seat, so that at the position at which the stem, 14^a, reaches 50 said valve, 15, both valves are off their seats. The valve, 15, being already leaned slightly away from its seat, tends to fall farther away therefrom to the wide-open position shown in Figure 2, at which it leans and is 55 stopped against the strainer. The float, 17, has on its upper side an upwardly-projecting stud, 17^c, which encounters the heel of the bell crank lever, 20, when the float rises to a certain height, and in the further rise for a 60 short distance rocks the lever over its fulcrum to swing its upper end inward for encounter with the valve, 14, to tilt it toward its upright position so far that the pin, 14^a, projects through the ports such distance as 65 to prevent the valve, 15, from being seated

by the suction. A check pin, 23, is provided in the chamber, 6, to limit the rise of the float beyond a proper point as indicated, so that it shall not by such further rise rock the valve, 20, so far as to force the valve, 14, 70 to and hold it upon its seat.

Upon considering this structure it will be seen that when by the action of the pulsator the liquid has been pumped in until the chamber, 6, is filled so far as to lift the float 75 to the point at which it operates the valves as described by means of the lever, 20, the valve, 15, will be held away from its seat so as not to be seated by the suction; and thereupon free atmospheric access being afforded 80 upon the suction stroke, no vacuum will be produced in the chamber, 6, and no further lifting of the liquid from the tank, 2, will be caused. Nevertheless, upon the pressure stroke, the valve, 14, will be seated as before, 85 and will not leave its seat to admit air until upon a suction stroke the absolute pressure in the cavity, 4^a, is less than atmospheric, and the pressure stroke will therefore operate to force the liquid out from the chamber, 90 6, and on into the carburetor, until the resultant lowering of the level of the liquid in the chamber, 6, causes the float to withdraw the lever, 20, from the valve, 14, and the pin, 14^a, of said lever from the valve, 15, so that 95 the latter valve may be closed upon the suction stroke of the pulsator, and the lifting of liquid from the tank to resume.

In the form shown in Figure 5, instead of a single diaphragm with a single aperture 100 forming two seats at its opposite ends, requiring two valves to control it, there is provided a valve chamber having a single valve in it adapted to oscillate it between two ports in the opposite walls of said valve chamber 105 so that one valve controlling two apertures is substituted for two valves controlling one aperture, as in Figure 2. The mode of operation is obviously the same. In each case there are two ports the valve means for controlling these ports respectively, by the opposite impulses of the pulsator. A convenient means of forming this valve chamber shown in Figure 5, consists in boring the boss, 4, clear through from end to end, and 110 counterboring it at opposite ends to form shoulders, 4^x, spaced apart a short distance, and forcing in from the opposite ends the two port members, 4^m and 4ⁿ, whose ends facing toward each other are set obliquely 115 to their axis to form a V-shaped valve chamber when they meet at the lower edge, in which valve chamber there is lodged a single valve, 14^x, which is tilted one way or the other from its vertical position for seating 120 upon the pressure stroke or upon the suction stroke of the pulsator. In this form the lever, 20^x, corresponding to the lever, 20, of the other form, has a slender pin terminal, 20^y, which projects through the port 125 130

in the right hand member of the valve chamber for checking the valve against seating by the suction.

I claim:—

- 5 1. In a structure for the purpose indicated, a pulsator, a chamber connected for experiencing suction and pressure from the respectively opposite impulses of the pulsator, a conduit adapted for connection on one hand with a low level supply tank and on the other hand with a carbureter, and comprising said chamber, check valves in said conduit, antecedent and subsequent respectively to said chamber, both opening for flow toward the carbureter, an atmosphere vent means for the chamber located beyond the communication of the pulsator with said chamber, said means comprising two ports in the path of air entrance to and emergence 15 from the chamber, through both of which successively the air passes in such entrance and emergence, and valve means for closing said ports adapted to be seated for closing 20
- them by movement in the direction of suction and pressure respectively, a float in the 25 chamber, and connections therefrom for stopping the suction-caused movement of said valve means at a predetermined high position of the float.
2. In a construction defined in claim 1 30 foregoing, means for arresting the rise of the float in the chamber at said predetermined position.
3. In the construction defined in claim 1, 35 foregoing, the valve-controlled means comprising a valve chamber having the two ports mentioned in opposite walls, a single valve in said chamber adapted to seat at either port, the float-operated means for stopping said valve being arranged for 40 reaching it through the port at which the valve is suction-seated.

In testimony whereof, I have hereunto set my hand at Chicago, Illinois, this 7th day of June, 1920.

CHARLES S. BURTON.
